TELEVISION RECEIVER

Emil I. Harman, Philadelphia, Pa., assignor to Philco Corporation, Philadelphia, Pa., a corporation of Pennsylvania

Application May 25, 1959, Serial No. 56,058

Term of patent 14 years

(Cl. D56—4)

FIG. 4.

FIG. 3.

Figure 1 is a perspective front view of a television receiver showing my new design;

Figure 2 is a view thereof generally similar to Figure 1 but wherein the visor of the receiver cabinet is open and the cabinet is in different position on the receiver stand;

Figure 3 is a side elevational view thereof; and

Figure 4 is a back elevational view thereof.

The dominant features of the design reside in the portions shown in full lines.

I claim:

The ornamental design for a television receiver, substantially as shown and described.
